UNITED STATES PATENT OFFICE.

OSCAR RICHARDS, OF MONTROSE, COLORADO.

TRANSPOSING MECHANISM FOR PIANOS, ORGANS, AND THE LIKE.

Application filed June 4, 1924. Serial No. 717,816.

This invention relates to pianos, pipe organs and reed organs, and particularly to transposing means therefor.

The general object of the invention is to provide means whereby a pianist or organist may transpose music from any key or pitch to any other key or pitch while at the same time fingering the piano or organ precisely the same as usual, that is, as the music is written, thus making it possible to play any piece of music in twelve different keys while fingering the same way every time.

A further object is to provide means whereby the keyboard or other action part of a piano, pipe organ or reed organ may be re-modeled so as to provide for this transposition of pitch or whereby an additional or upper keyboard may be disposed within the piano, organ or the like for the same purpose or to provide a portable attachment adapted to be placed upon the keyboard of a piano and readily put in place or removed therefrom.

A still further object is to provide a construction of this character wherein in certain forms of the invention the transposing attachment is shiftable longitudinally along beneath the keys or over the keys by means of racks and gear wheels, thus permitting the manually operable finger wheel to be provided with indicia indicating the extent to which the keyboard has been shifted.

Another object is to provide means whereby the abstracts or wippens may be lifted so as to permit the movement of the transposing keys, and to provide means whereby the cam which controls this lifting movement may be actuated from the front of the piano or organ.

Other objects have to do with the details of construction and arrangement of parts as will appear more fully hereinafter.

My invention is illustrated in the accompanying drawings, wherein:—

Figure 1 is a sectional view through a piano easing showing my transposing keyboard and transposing key bed or frame;

Figure 2 is a vertical sectional view through a piano action and the keyboard, my transposing keyboard being partly shown in elevation;

Figure 3 is a fragmentary side elevation of the rack and pinion whereby to secure the shifting of the transposing keyboard;

Figure 4 is a side elevation of the means whereby the cam 10^b may be actuated;

Figure 5 is a top plan view of a transposing keyboard constructed somewhat differently from the keyboard shown in Figure 1 but also shifted by means of the rack and pinion heretofore referred to.

Referring to Figures 1 and 2, it will be seen that I have illustrated in Figure 2 an ordinary piano action where 2 is the hammer rail and 1 the action rail, 3 the tongue rail, 4 the tongue, 5 the abstract, 6 a supporting bracket, 7 the wippen, 8 the usual key, and 9 the capstan screw. This capstan screw of all of the abstracts 5 should be carried by the abstracts 5 and not by the keys 8 so that different adjustments are made to take up lost motion in the piano action and the keys 8 will at all times remain perfectly level. It will be understood, of course, that the piano action is typical merely and that many variations of this piano action might be used with my invention.

It will be also seen that I have not illustrated all the parts of the action but merely enough to identify it as an action. Mounted in bearings 53 in the ends A of the frame of the piano action is a transversely extending cam 10 (see Figures 1 and 2) which extends entirely across the piano and is supported immediately below all of the tongues 4 so that as this cam 10 is oscillated in one direction it will lift up on all of the tongues 4 and, therefore, lift up on all of the wippens 5 and the capstan screws 9, leaving the capstan screws entirely above the keys 8. This cam 10 is oscillated by means of an arm 10^a connected to a rod 11 which extends through the front of the case and is provided with a button whereby it may be operated. This rod is preferably provided with a ratchet notch 11^a whereby the cam may be held in its lifter-raising position by simply engaging the notch with the front of the piano case.

Where pianos do not have the tongues 4 nor the abstracts 5 as, for instance, in certain makes of pianos, as in the Marshall & Wendell upright piano and others, the cam 10 is not disposed below the tongues 4, there being no tongues 4, but this cam is shown as disposed in dotted lines 10^b in Figure 2 and immediately beneath the wippen so that the operation of the cam will lift the wippen up and thus cause a clearance between the wip-

pens and the keys or key projections. The means for operating this cam 10^b is shown in Figure 5, where a bell crank lever 17 is provided connected by a link 18 to an arm 5 extending from the member 10^b, the depending arm of the bell crank 17 being connected to an operating rod 11^b which extends through to the front of the piano.

One of the forms of my invention and the 10 form which is illustrated in Figures 1 and 2 consists of a movable keyboard or key bed 26 which has either more, less or as many keys as the regular keyboard of the piano. This keyboard is mounted on rollers 13 (see 15 Figure 2), there being a plurality of pairs of these rollers, each pair being arranged upon a shaft 16, each of these rollers being provided with gear teeth 14 operating upon a rack formed in or carried by the longitudinal frame members 15. The outer end of the shaft 16 carries upon it a head 12 whereby it may be operated, and thus it will be seen that by turning this head 12 in one direction or the other the whole frame 20 consisting of the pieces 15 and the transverse pieces 15^a and the keys supported thereby, as will be later described, may be shifted in one direction or the other relative to the abstracts 5 or the wippens 7. Keys are 25 mounted upon the usual key rail 8^a having the usual key button and key pin.

It will be obvious that a depression of the key 8 will cause a lifting up of the abstracts 5 and the operation of the hammer 30 21 in the usual manner. The keys 8 are straight and equi-distant, as shown in Figure 1, and the lifters or abstracts 5 and the hammers 21 are to be equi-distant also and, of course, the strings or unisons 19 which 35 can be accomplished by mounting all of the strings in parallel relation to each other. This, of course, would require the rails 1, 2 and 3 to be made stronger and to be supported from the ends alone or reinforced if 40 need be by metal beams or rods running full length of the rails. I have not illustrated this, as this forms no part of my invention and will, of course, be obvious to any manufacturer of pianos.

It will be obvious that with this construction it is only necessary in transposing for the keyboard 26 to be shifted longitudinally in one direction or the other to the degree required to make the transposition. The 50 keyboard may have more keys than are used in the ordinary piano so that whether it is shifted in one direction or the other there would always be keys in connection with every abstract 5, or the keyboard could have 55 the usual length and when in its usual or normal position there would be a key beneath every abstract 5, but in this latter case when the keyboard was shifted either in one direction or the other either some of the 60 highest treble strings would be out of action

or the lowest bass strings would be out of action. Inasmuch as the highest treble strings and lowest bass strings are not often used, this would not render the piano practically inoperative.

In the operation of this mechanism, when the piano is used in the ordinary manner the keys 8 are disposed immediately below their usual abstracts, but when it is desired to transpose a piece of music the cam 10 is 70 operated by means of the pull rod 11 and the tongue 4 and the abstract 5 raised just sufficiently to permit the keys and the frame upon which they are mounted to be shifted longitudinally by means of the toothed 75 rollers 13 and the operating handle 12. The operating handle 12 may be provided with a series of indicia indicating the extent to which the operating handle 12 is turned so that the operator will know 80 exactly to where the keys have been adjusted. After the supporting frame for the keys, or in other words the key bed has been adjusted to the proper transposing position, the cam 10 is shifted again to the full 85 line position in Figure 2 so as to lower the abstracts 5 onto the rear ends of the keys 8 and the piano is then in condition for playing.

In the ordinary piano the action is supported in four places at each end and by action brackets which rest upon the rear of the key bed between the V-shaped spaces 28 shown in Figure 4. The construction shown in Figures 1 and 2 where there is only one 90 keyboard which shifts sidewise would not permit the use of these two medially disposed action brackets at the points 28, as there are no V-shaped spaces between the keys in Figures 1 and 2 and there must not be in this 95 construction, for if there were then when the keyboard was shifted sidewise some of the keys would come into this V-shaped space at the rear, where with the ordinary construction there are no abstracts or jack 100 rockers and some of the keys would, therefore, become useless and silent, which would be disastrous and unsatisfactory to any 105 musician. This does not matter with the keys, as before explained, in the low bass 110 or extremely high treble, as these keys are seldom used, but all the keys near the center of the keyboard must be operative at all times. Thus with the construction shown in Figures 1 and 2 the action would have to be 115 made strong enough so as to be supported at the ends alone, as there could be no action brackets near the center. This strengthening of the action could be accomplished by increasing the size and strength of the rails 1, 120 2 and 3 shown in Figure 2, and if the manufacturer desired these rails could be still further increased by bracing them with anchor irons.

The construction shown in Figures 1 to 4 125

could be applied to pianos by re-modeling the pianos or applied initially. It will be understood the same principle might be applied to pipe organs or reed organs.

5 While I have illustrated and described three several embodiments of my invention, I do not wish to be limited to the details of construction shown therein, as it is obvious these might be changed in many ways without departing from the spirit of the invention.

10 I claim:—

1. In a keyed musical instrument, the combination with the action thereof, of keys mounted for movement beneath the action and adapted thereby to register with the action in a plurality of positions, a frame supporting the keys including longitudinally extending rack bars, a plurality of 15 shafts extending at right angles to the rack bars and mounted upon the frame of the instrument, one of the shafts extending out through the front of the instrument, a plurality of pairs of rollers mounted upon the 20 shafts and having meshing engagement with the rack bars, each of said rollers having opposed flanges embracing the rack bars and that shaft extending through the front of the instrument having a finger hold 25 whereby it may be operated.

30 2. In a musical instrument, the combination with the action thereof, of keys mounted for movement beneath the action and adapt-

ed thereby to register with the action in a plurality of positions, a key bed upon which 35 the keys are fulcrumed, longitudinally extending rack bars upon which the key bed is mounted, a plurality of shafts extending at right angles to the rack bars and mounted upon the frame of the instrument, a plural- 40 ity of pairs of flanged rollers mounted upon the shafts and meshing with the rack bars, and manually operable means for rotating one of said shafts.

3. In a piano, the combination with the 45 piano action, including a plurality of abstracts, one for each key, of keys mounted for movement beneath the abstract and normally engaging the same, said keys being adapted to register with the abstracts in a 50 plurality of positions, a frame supporting the keys including longitudinally extending rack bars, a plurality of shafts extending at right angles to the rack bars and mounted upon the frame of the piano, a plurality of 55 pairs of flanged rollers mounted upon the shafts and having meshing engagement with the rack bars, means for rotating one of said shafts, a member disposed behind all of the abstracts and above the keys, and manually 60 operable means extending from the front of the piano whereby said member may be operated to raise or lower the abstracts out of or into engagement with the keys.

OSCAR RICHARDS.
